UNITED STATES PATENT OFFICE.

ARTHUR ATWATER KENT, OF ARDMORE, PENNSYLVANIA.

PANEL CONDENSER.

Application filed May 12, 1925. Serial No. 29,658.

To all whom it may concern:

Be it known that I, ARTHUR ATWATER KENT, a citizen of the United States, residing at Ardmore, county of Montgomery, and 5 State of Pennsylvania, have invented certain new and useful Improvements in Panel Condensers, of which the following is a specification.

My invention relates to variable electrical condensers of the plate type for variation of capacity, as in tuning of circuits, particularly circuits traversed by high frequency current or oscillations, as in radio systems.

10 In accordance with my invention the panel, plate or wall of a radio receiving set, and more particularly the metal panel or wall of a cabinet enclosing the receiving set, is comprehended in or is a component part of a condenser structure or unit comprising a stator element of one or more plates carried upon a bolt or rod secured, independently of the rotor and its support, to the panel or wall, either directly, or to 25 an insulating member which in turn is secured directly to the panel or wall.

My invention resides in structure of the character hereinafter described and claimed.

For an illustration of one of the forms 30 my invention may take, reference is to be had to the accompanying drawing, in which:

Figure 1 is a vertical sectional view, partly in elevation, of structure embodying my invention.

35 Fig. 2 is a rear elevational view of the structure shown in Fig. 1.

Fig. 3 is a horizontal sectional view, partly in plan, of structure shown in Fig. 1.

40 Fig. 4 is an end elevational view of the spring.

Referring to the drawing, 1 is the sheet metal panel, plate or wall, of a cabinet or housing containing the elements of a radio receiving set, as described in my application 45 Serial No. 28,808, filed May 8, 1925, and is comprehended in or is a component of one or more condenser units of the receiving set.

50 On the inner side of the panel 1 is the ledge member 2 of sheet metal, having the downwardly extending flange 3 secured, as by spot-welding, to the panel 1.

Upon the ledge member 2 may be carried other devices or elements of the radio re-

ceiving set with which co-operates the condenser structure illustrated.

The rotor bearing member 4 is in the form of a metal sleeve, preferably chambered as indicated at 5. The bearing sleeve 4 has on its exterior a portion 7 of reduced diameter 55 extending through a hole of similar diameter in the panel 1, with its ends spun or worked over into the form of the flange 7a, between which and the shoulder on the sleeve 4 the panel 1 is snugly gripped, 60 whereby the bearing sleeve 4 is rigidly fixed to the panel.

At its end remote from the plate 1 the sleeve 4 is provided with a conical or equivalent seat 8, upon which bears the conical or similar enlargement 9 on the rotor shaft 10, which latter rotates upon the bearings 6 and 8 in the sleeve 4 and projects beyond the same to the opposite or front side of the plate 1, where there is secured to the shaft 10 the operating handle or knob 11, integral 70 with which is the dial 12, carrying the usual graduations for co-operation with a pointer or marker on the plate 1. The members 11 and 12 are preferably constituted of molding 75 insulating material, such as bakelite or the like. Molded in the knob structure is the metallic insert member 13 through a wall of which extends the set screw 14 for securing 80 the sleeve 13, and therefore the knob and dial, to the shaft 10, whereby the shaft 10 may be rotated to effect adjustment of the 85 hereinafter described rotor structure.

Between the end of member 13 and the plate 1 is disposed the bowed spring 15, having the hole or aperture 16 through which the shaft 10 loosely extends. The spring 15 is held under compression between the member 13 and plate 1, thereby exerting a longitudinal thrust toward the left upon the shaft 10, as viewed in Fig. 1, causing the conical bearing 9 of the shaft snugly to bear in the conical bearing 8 in the bearing member 4. The spring 15 is free or floats 90 between the members 1 and 13, for it is not secured to either of those members or to any other member.

Upon the part of the shaft 10 overhanging beyond or extending to the right of the bearing member 4, as indicated in Fig. 1, are secured one or more parallel conducting leaves or plates 17 constituting the rotatable armature assembly or rotor element of the 100 105

condenser. These plates or leaves 17 may be secured to the shaft 10 in various ways well understood in the art. In the example illustrated, however, the leaves 17 and a cylindrical hub portion 18 are an integral casting, which may be die cast upon the shaft 10, which latter is preferably of steel or the like.

Co-acting with the rotor plates 17 are the 10 stator plates or leaves 19 disposed substantially parallel with each other and suitably spaced to permit interleaving therewith of the rotor plates, as well understood in the art.

15 The stationary armature plate assembly or stator comprises the plates 19 through apertures in which extend the rods or bolts 20. Surrounding each of the rods or bolts 20 and serving as spacers for the plates 19 are 20 the washers 21. The nut 22, threaded upon each of the rods 20, serves as an abutment between which and a washer 23, held by a nut 24, the plates 19 and washers 21 are confined.

25 The several rods or bolts 20 may be directly and individually secured to the panel or plate 1, but, as indicated, and particularly when the rotor is in electrical communication with the metal panel 1, there is 30 utilized for each bolt 20 an intervening member 25 of insulating material secured to the panel 1 by any suitable means, as for example by screw 26.

The members 25 are preferably threaded 35 onto the bolts or rods 20 as indicated, and the position of the stator structure longitudinally of the axis of the shaft 10 is adjustable and determinable by the nuts 27 threaded upon the bolts or rods 20 and abutting 40 against the members 25.

The structure above described is broadly 45 of the character disclosed in the aforesaid application, particularly in that the stator structure is supported upon or secured to the panel 1 independently of the mounting or support of the rotor element, whereby the panel 1 is a component part of the condenser unit, and whereby the positions of the rotor and stator elements with respect 50 to each other are determined by their respective independent attachments to the panel 1. In the structure herein described and claimed the stator element is attached to the panel 1 at one or more points, each of the attachments is adjustable to effect adjustment of distance of the stator structure 55 from the panel 1 and, preferably, each attachment comprises a member of insulating material for supporting and determining the distance of the stator structure from the panel 1 and for insulating the stator structure from the panel.

What I claim is:

60 1. The combination with a panel, of rotor and stator elements of a condenser, a sup-

port for said rotor element on said panel, said stator element comprising a rod, plate structure carried by said rod in co-operative relation with the plate structure of the rotor element, and means securing said rod to said panel independently of said rotor support, whereby said panel is included in a condenser unit with said rotor and stator elements. 70

2. The combination with a panel, of rotor 75 and stator elements of a condenser, a support for said rotor element on said panel, said stator element comprising a rod, plate structure carried by said rod in co-operative 80 relation with the plate structure of the rotor element, a support for said rod secured to said panel independently of said rotor support to include said panel in a condenser unit with said rotor and stator elements, and means for effecting longitudinal adjustment 85 of said rod with respect to said rod support.

3. The combination with a panel, of rotor 90 and stator elements of a condenser, a support for said rotor element on said panel, said stator element comprising a rod, plate structure carried by said rod in co-operative relation with the plate structure of the rotor element, a support of insulating material for said rod secured to said panel independently of said rotor support to include 95 said panel in a condenser unit with said rotor and stator elements, and means for effecting longitudinal adjustment of said rod with respect to said rod support. 100

4. The combination with a panel, of rotor 105 and stator elements of a condenser, a support for said rotor element on said panel, said stator element comprising a plurality of rods, a plurality of plates spaced from each other and carried by said rods and with which rotor plates co-act, and means for individually securing said rods on said panel independently of said rotor support for including said panel in a condenser unit 110 with said rotor and stator elements.

5. The combination with a panel, of rotor 115 and stator elements of a condenser, a support for said rotor element on said panel, said stator element comprising a plurality of rods, a plurality of plates spaced from each other and carried by said rods and with which rotor plates co-act, and means for securing said stator element on said panel independently of said rotor support to include 120 said panel in a condenser unit with said rotor and stator elements, said means comprising individual supporting members for said rods secured independently of each other to said panel.

6. The combination with a panel, of rotor 125 and stator elements of a condenser, a support for said rotor element on said panel, said stator element comprising a plurality of rods, a plurality of plates spaced from each other 130

- and carried by said rods and with which rotor plates co-act, and means for securing said stator element on said panel independently of said rotor support to include said panel in a condenser unit with said rotor and stator elements, said means comprising individual supporting members of insulating material for said rods secured independently of each other to said panel.
- 5 7. The combination with a panel, of rotor and stator elements of a condenser, a support for said rotor element on said panel, said stator element comprising a plurality of rods, a plurality of plates spaced from each other and carried by said rods and with which rotor plates co-act, means for securing said stator element on said panel independently of said rotor support to include said panel in a condenser unit with said rotor and stator elements, said means comprising individual supporting members of insulating material for said rods secured independently of each other to said panel, and 10 means for adjusting said rods longitudinally with respect to said rod supporting members.
- 15 8. The combination with a panel, of rotor and stator elements of a condenser, a support for said rotor element on said panel, said stator element comprising a plurality of rods, a plurality of plates spaced from each other and carried by said rods and with which rotor plates co-act, means for securing said stator element on said panel independently of said rotor support to include said panel in a condenser unit with said rotor and stator elements, said means comprising individual supporting members of insulating material for said rods secured independently of each other to said panel, and 20 means for adjusting said rods longitudinally with respect to said rod supporting members.
- 25 9. The combination with a panel, of rotor and stator elements of a condenser, a support for said rotor element on said panel, said stator element comprising a plurality of rods, a plurality of plates spaced from each other and carried by said rods and with which rotor plates co-act, means for securing said stator element on said panel independently of said rotor support to include said panel in a condenser unit with said rotor and stator elements, said means comprising individual supporting members of insulating material for said rods secured independently of each other to said panel, and 30 means for adjusting said rods longitudinally with respect to said rod supporting members.
- 35 10. The combination with a panel, of rotor and stator elements of a condenser, a support for said rotor element on said panel, said stator element comprising a plurality of rods, a plurality of plates spaced from each other and carried by said rods and with which rotor plates co-act, means for securing said stator element on said panel independently of said rotor support to include said panel in a condenser unit with said rotor and stator elements, said means comprising individual supporting members of insulating material for said rods secured independently of each other to said panel, and 40 means for adjusting said rods longitudinally with respect to said rod supporting members.

ARTHUR ATWATER KENT.
